UNITED STATES PATENT OFFICE.

GUSTAV A. OLSON, OF ALBERT LEA, MINNESOTA.

OVERHEAD-TRACK SWITCH.

1,034,284.

Specification of Letters Patent. Patented July 30, 1912.

Application filed June 28, 1911. Serial No. 635,801.

To all whom it may concern:

Be it known that I, GUSTAV A. OLSON, a citizen of the United States, residing at Albert Lea, in the county of Hennepin and State of Minnesota, have invented certain new and useful Improvements in Overhead-Track Switches; and I do hereby declare the following to be a full, clear, and exact description of the invention, such as will 5 enable others skilled in the art to which it appertains to make and use the same.

My invention has for its object to provide an improved overhead track switch especially adapted for use in connection 15 with litter carriers, but adapted, nevertheless, for more general use.

To the above ends, the invention consists of the novel devices and combinations of devices hereinafter described and defined in 20 the claims.

In the accompanying drawings which illustrate the invention, like characters indicate like parts throughout the several views.

Referring to the drawings, Figure 1 is a 25 perspective view with parts broken away showing the improved switch with a switch rail arranged for coöperation with a main line rail and two branch line rails; Fig. 2 is a plan view of the parts shown in Fig. 1; Fig. 3 is a vertical section on the line $x^3 x^3$ of Fig. 2; Fig. 4 is a vertical section 30 taken approximately on the line $x^4 x^4$ of Fig. 2; Fig. 5 is a horizontal section taken on the line $x^5 x^5$ of Fig. 4; and Fig. 6 is a detail 35 in section taken approximately on the line $x^6 x^6$ of Fig. 1, some parts being removed and some being broken away.

The numeral 1 indicates a main line rail which is supported by the lower ends of 40 hanger brackets 2 that are rigidly secured at their upper ends by suitably supported over-head beams or bars 3. At the switch, the main rail 1 is cut away for sufficient distance to permit of the insertion of a 45 switch rail 4 which, at one end, is pivoted or hinged to an adjacent section of the main rail at 5.

The numerals 6 and 7 indicate the branch line rails which diverge from the main rail 50 and are laterally spaced therefrom by a line in the same horizontal plane as the said main rail and switch rail. These branch line rails 6 and 7 are secured to the lower ends of hanger brackets 8 and 9, the upper 55 ends of which are suitably secured to overhead beams or bars 10 and 11, respectively.

The converging ends of the so-called branch rails 6 and 7 are spaced from the switch rail pivot 5 equal distances and the same distance as the length of the gap left in the 60 main rail for the insertion of the switch rail 4. Preferably also, the converging ends of the branch rails 6 and 7 and the end of the laterally adjacent section of the main rail 1 are beveled or made wedge-shaped. At 65 its free end, the switch rail 4 is provided with a short pivoted nose or supplemental section 12, the free end of which is beveled or made wedge-shaped and is so extended that it will engage with the beveled ends 70 of the branch rails 6 and 7 and with laterally adjacent sections of the main rail 1. This nose or supplemental section 12 is normally held in the plane of the switch rail 4, by opposing flat springs 13 secured to 75 opposite sides of the said switch rail.

The free end of the switch rail 4 is secured to the lower end of a hanger bracket 14, the upper end of which is secured to a sliding cross-head 15, which, in turn, is guided 80 for horizontal oscillatory movements by a cross-head guide bar 16. This guide bar 16 is rigidly secured to the supporting beams 3, 10 and 11 by suitable brackets 17 and 18, shown as cast integral, respectively, 85 with the hanger brackets 2, 8 and 9. As preferably constructed, the concave edge of the guide bar 16 is formed with a projecting flange 16^a; the curve of which is concentric to the projecting axis of the switch rail 90 pivot 5. The cross-head 15 has a groove that engages with the said flange 16^a (see particularly Figs. 1 and 6). The ends of the guide bars 16 are provided with cable guides shown as afforded by simple perforations 19. A switch actuating cable 20 having depending ends within easy reach from the ground or floor is passed through the guide perforations 19, and its intermediate portion is rigidly attached by a staple 95 21 or other suitable means to the cross-head 15. All of the hanger brackets 2, 8 and 9 are laterally off-set from the rails supported thereby so that truck wheels of a litter carrier or other traveler may freely 100 run on the said rails.

As is evident, by pulling on the proper end of the cable 20 the switch rails 4 may be moved into alignment with either of the branch rails 6 or 7, or with the coöperating 110 intermediate rail section, to-wit, the extended section of the main track rail. When

- the switch rail is moved past the intermediate rail or extended main rail sections, the yieldingly held nose-piece 12 will yield and clear the same, but when left standing in alignment therewith so as to close or complete the main rail, it will overlap the bevelled end thereof and afford a straight rail upon which the truck wheels can run. The pivoted nose section 12 is serviceable only when the switch rail is arranged for co-operation with more than two track rails, and when the same is used, any desired number of intermediate rails may be employed and the switch rail will overlap therewith when set into alignment with any one thereof.

As a simple and efficient means for frictionally holding the switch rail 4 in any one of its several positions, frictional clamps are applied to the ends of the guide bar 16. These frictional clamps are preferably in the form of metal clamps 22 loosely attached at one end to the said bar 16 with their free ends engaging the cable. Thumb screws 23 work loosely through perforation in the clamps 22 and are screwed into the ends of the bars 16. Coiled springs 24 are compressed between the clamps 22, and the heads of the respective thumb screws 23. As is evident, by adjustments of the thumb screws 23, any desired friction may be applied to the operating cable 20 by means of the clamps 22. These frictional clamps, in practice, have been found sufficient when properly adjusted, to hold the switch rail 4 in any one of its several operative positions.

The improved switch above described has been found highly serviceable in connection with litter carriers, but, as already indicated, is capable of more general use.

What I claim is:

1. The combination with a main track rail and a pivoted switch rail in connection therewith, of a multiplicity of branch rails in approximately the same horizontal plane with their ends terminated equidistant from the pivotal support of the said switch rail with which the free end of said switch rail is adapted to be co-operatively aligned, and the said switch rail, at its free end, having a pivoted nose yieldingly held in an intermediate position and arranged to overlap with the ends of the said branch rails and to yield and pass over the end of an intermediate branch rail.

2. The combination with an overhead rail supporting structure having depending rail supporting brackets, of a main rail and a multiplicity of laterally spaced branch rails supported by the said depending brackets, a pivoted switch rail in connection with said main rail, a crosshead guide supported by the said overhead structure and extended concentric to the projected axis of the

switch rail pivot, and a crosshead slidably mounted on said crosshead guide and having a depending bracket supporting the free end of said switch rail.

3. The combination with an overhead rail supporting structure having depending rail supporting brackets, of a main rail and a multiplicity of laterally spaced branch rails supported by the said depending brackets, a pivoted switch rail in connection with said main rail, a crosshead guide supported by the said overhead structure and extended concentric to the projected axis of the switch rail pivot, a crosshead slidably mounted on said crosshead guide and having a depending bracket supporting the free end of said switch rail, and an operating cable connected to said crosshead, and having its depending ends extended downward through guides located on opposite sides of the said crosshead.

4. The combination with an overhead rail supporting structure having depending rail supporting brackets, of a main track rail and a multiplicity of laterally spaced branch rails supported by the said brackets, a switch rail pivotally connected to said main track rail and provided at its free end with a pivoted nose yieldingly held in an intermediate position and arranged to overlap and engage with the said branch rails, a crosshead guide supported by said overhead structure and having a guiding surface extended concentric to the projected axis of the switch rail pivot and having, at its ends, suitable cable guides, a crosshead supported and guided by said crosshead guide and provided with a bracket attached to and supporting the free end of said switch rail, and an operating cable attached to said crosshead and having its ends working downward through the cable guides on the ends of the said crosshead guide.

5. The combination with a main track rail and a pivoted switch rail in connection therewith, of a multiplicity of branch rails in approximately the same horizontal plane with their ends terminated equidistant from the pivotal support of the said switch rail, and with which the free end of said switch rail is adapted to be co-operatively aligned, a cable connection for operating said switch rail, and a friction device engageable with and for holding said cable connection.

6. The combination with an overhead rail supporting structure having depending rail supporting brackets, of a main track rail and a multiplicity of laterally spaced branch rails supported by the said brackets, a switch rail pivotally connected to said main track rail and provided at its free end with a pivoted nose yieldingly held in an intermediate position and arranged to overlap and engage with the said branch rails, a crosshead guide supported by said over-

head structure and having a guiding surface extended concentric to the projected axis of the switch rail pivot and having, at its ends, suitable cable guides, a crosshead supported and guided by said crosshead guide and provided with a bracket attached to and supporting the free end of said switch rail, an operating cable attached to said crosshead and having its ends working downward through the cable guides on the ends of the said crosshead guide, and adjustable frictional devices applied to the said operating cable for frictionally holding the switch rail in its different operative positions.

7. The combination with a main track rail and a pivoted switch rail in connection therewith, of branch rails in approximately the same horizontal plane with their ends terminated approximately equidistant from the pivotal support of the said switch rail, and frictional means for holding the free end of said switch rail co-operatively alined with the ends of said branch rails.

In testimony whereof I affix my signature in presence of two witnesses.

GUSTAV A. OLSON.
